(57) **CLAIM**

The ornamental design for a display screen or portion thereof with graphical user interface, as shown and described.

DESCRIPTION

FIG. 1. is a front view of a display screen or portion thereof with a graphical user interface showing a first embodiment of the claimed design;

FIG. 2. is a front view of a display screen or portion thereof with a graphical user interface showing a second embodiment of the claimed design;

FIG. 3. is a front view of a display screen or portion thereof with a graphical user interface showing a third embodiment of the claimed design;

FIG. 4. is a front view of a display screen or portion thereof with a graphical user interface showing a fourth embodiment of the claimed design;

FIG. 5. is a front view of a display screen or portion thereof with a graphical user interface showing a fifth embodiment of the claimed design; and,

FIG. 6. is a front view of a display screen or portion thereof with a graphical user interface showing a sixth embodiment of the claimed design.

The broken lines in the figures depict portions of the graphical user interface or display screen that form no part of the claimed design.

FIGS. 4 and 6, are illustrated to show contrasting appearance. Areas of the design having different levels of stippling represent areas with contrasting appearances.

The Applicant reserves the right to claim any part, portion, element and/or combination thereof of the disclosed designs, including to replace any solid line with a broken line to disclaim any part, portion, element and/or combination thereof of the disclosed design, or to replace any broken lines with a solid line to claim any part, portion, element and/or combination thereof of the disclosed design.
